UNITED STATES PATENT OFFICE.

JAMES F. McELROY, OF ALBANY, NEW YORK, ASSIGNOR TO CONSOLIDATED CAR HEATING COMPANY, A CORPORATION OF WEST VIRGINIA.

AIR-BRAKE.

No. 901,923.

Specification of Letters Patent.

Patented Oct. 20, 1908.

Application filed March 2, 1907. Serial No. 360,281.

To all whom it may concern:

Be it known that I, JAMES F. McELROY, a citizen of the United States, residing at Albany, county of Albany, State of New York, have invented certain new and useful Improvements in Air-Brakes; and in the following specification and accompanying drawings I have described and illustrated that form of my invention which I now consider as the best out of the various forms in which its principles may be embodied.

In the drawings Figure 1 is a side elevation of my triple valve; Fig. 2 is a vertical, axial section taken at right angles to the view in Fig. 1.

My invention relates to air brakes and consists of certain improvements applicable particularly to air brakes of the type shown in my Patent No. 768,587, dated August 23, 1904.

More specifically, I have devised a new arrangement of the valve which, in brakes of my type, serves to supply the auxiliary reservoir from the train-line, and to admit train-line air to the brake cylinder in advance of the admission thereto of air from the auxiliary reservoir, in the event of a sudden application of the brakes. I have also devised an arrangement which serves to equalize the time required for brake-release on different cars of a train.

In brakes of the type shown in my aforesaid patent, the inlet and exhaust valves of the brake cylinder are controlled by the resultant of three component pressures, to-wit the train-line and brake-cylinder pressures acting in opposition to a standard pressure. By this means the pressure in the brake cylinders follows inversely the pressure in the train line at a ratio dependent upon the mechanical advantage of the train-line pressure with respect to the brake-cylinder pressure, whereby a given decrease in the former corresponds to a considerable larger increase in the latter.

Turning to the accompanying drawing, A represents a triple valve embodying my invention. It corresponds to the triple valve of the ordinary Westinghouse system and is interchangeable therewith, being provided with a base plate A' designed to be bolted to the auxiliary reservoir in the usual manner, it being understood that my device may be used to advantage in connection with Westinghouse brakes, and controlled by the or-

dinary Westinghouse engineer's valve, although its full value is only realized with my form of engineer's valve. The casing of the triple valve is divided horizontally into three sections a' a^2 a^3 , diaphragms C D being interposed between the sections and held in place by the bolts which join the sections together. The two diaphragms C and D are joined by a hollow stem E, the upper end of which forms the seat of the valve k^2 which, together with a similar valve k' , is mounted on the vertical valve stem K. The valve k' is the inlet and k^2 the exhaust valve of the brake-cylinder, which is in communication with the chamber 5 located between the two valves. A passage 7 admits the brake-cylinder pressure from the chamber 5 to the chamber 4 where it acts on the upper side of the diaphragm D. The chamber 3 between the two diaphragms is in communication with the train-line by means of the passage 2 which leads from the chamber 1 into which the train-line enters. Below the aforesaid stem E is the spring G which acts thereon through a spherical joint and is limited by the stops d d . The spring at its lower end bears against the adjusting screw H.

It will be observed that, as a normal condition of equilibrium, both the train-line pressure and the brake-cylinder pressure (the latter acting on a lesser diaphragm area than the former) coöperate in opposition to the pressure of the standard spring G and hold both inlet and exhaust valves closed. Consequently, assuming the parts to be thus in equilibrium, any diminution of train-line pressure which may not be counterbalanced by a corresponding increase of brake pressure, will disturb the equilibrium and will allow the spring G to rise and lift the inlet valve k' from its seat. This will admit pressure from the chamber 6 (which is either the auxiliary-reservoir pressure or the train-line pressure) to the brake cylinder through the chamber 5, and this flow from the chamber 6 to the brake cylinder will continue until the increase of brake pressure is sufficient to compensate for the decrease in train-line pressure. When this point is reached the spring G will be re-compressed and allow the inlet valve k' to close, thus restoring the equilibrium. Conversely, an increase in train-line pressure will cause a compression of the spring and open the ex-

haust valve k^2 , by a depression of its seat, and thereby release the brake pressure through the hollow stem E and the casing of the spring G which acts as a muffled exhaust outlet; the exhaust flow will continue until the decrease in brake pressure compensates for the increase in train-line pressure and equilibrium is again restored and the spring G closes the exhaust valve k^2 . By 5 this means the brake-cylinder pressure follows inversely the train-line pressure according to a ratio determined by the relative diaphragm areas acted upon by the two pressures.

10 In the present application I do not undertake to make any claim upon the construction thus far described.

Between the aforesaid chamber 6 and the train-line chamber 1 I interpose a check-valve P having a hollow stem p' with openings therein through which chamber 6 communicates with chamber 9, which in turn, communicates by the passage shown in dotted lines, with a chamber 10. Between 15 the chamber 10 and the chamber 11 is interposed a check-valve P' which opens by lifting upward and the chamber 11 communicates with the auxiliary reservoir through the chamber 8. A small feed groove p^2 maintains communication between the chambers 10 and 11 around the valve P'. Whenever 20 the train-line pressure in chamber 1 exceeds the auxiliary-reservoir pressure in chamber 6, the valve P lifts and the train-line air then flows to the chamber 6, and feeds the auxiliary reservoir through the hollow stem p' , the chamber 9, the chamber 10, feed groove p^2 , chamber 11, and thence to the auxiliary reservoir through chamber 25 8. Conversely, when the valve P is closed, the auxiliary-reservoir pressure follows the reverse route but has a freer passage, because it lifts the valve P' and passes freely through it. It also acts downwardly 30 through the hollow stem p' upon the valve P tending to close it. When the valve P is lifted the holes in its hollow stem p' are nearly closed by the surrounding walls, leaving only a sufficient opening to supply air 35 to the feed groove p^2 , and this practically shuts off the flow from the auxiliary reservoir to the chamber 6, the chamber 6 being then supplied directly from the train line.

40 It will be understood that normally the three pressures aforesaid are in a state of equilibrium, the train-line pressure and the brake-cylinder pressure balancing the standard-spring pressure and maintaining both inlet and exhaust valves of the brake cylinder closed. This is the condition when the 45 brakes are entirely released and also when they are applied at some constant pressure determined by the degree of train-line pressure, which in turn is under the control of the engineer. This state of equilibrium is

disturbed as heretofore explained, by variations in the train-line pressure, and the effect is different as the variation in train-line pressure is sudden or gradual. If the change is very gradual, it does not lift the valve P, 50 except that on release of the brakes it may lift it slightly to a degree sufficient to allow the train line to feed the auxiliary and make up for any depletion thereof. Thus if there is a gradual reduction in train-line pressure, 55 as in ordinary service application of the brakes, the equilibrium aforesaid will be distributed and the inlet valve k' leading to the brake cylinder will be opened, but only the air from the auxiliary reservoir will flow 60 through the open inlet valve to give a brake-cylinder pressure sufficient to compensate for the decrease in train-line pressure and thereby restore the equilibrium. On the contrary, if the reduction in the train-line pressure is made suddenly, the valve k' will be thrown wide open, thereby emptying chamber 6 into the brake cylinder so suddenly as to practically eliminate the pressure in chamber 6 and allow the valve P to rise by 65 virtue of the train-line pressure beneath it. The rising of the valve P will, in the way I have described, shut off the auxiliary-reservoir air from the chamber 6, but admit to that chamber the train-line air. It will 70 therefore be the train-line air instead of the auxiliary-reservoir air which will first flow into the chamber 6 and thence into the brake cylinder. This will not only give a strong and sudden application of the brakes, but 75 will also tend to deplete the train line and thereby expedite the drop in train-line pressure upon which this violent application of the brakes depends. This constitutes my 80 emergency operation and provides for a definite serial or successive inflow of train-line and auxiliary-reservoir air to the brake cylinder. Of course the flow of train-line air into chamber 6 will only continue until the 85 train-line pressure drops sufficiently to allow 90 the auxiliary-reservoir pressure, acting downwardly on the valve P through its hollow stem p' , to overcome the train-line pressure and close the valve. Then the auxiliary reservoir will be the source of supply for the 95 chamber 6 and the brake cylinder, and the air therefrom will flow into the brakes until the brake pressure rises sufficiently to restore the equilibrium by compensating for the 100 reduction of train-line pressure and so restoring the balance of pressures which will maintain valves k' and k^2 , both of them, closed. Upon the subsequent release of the brakes, by the restoration of the train-line pressure, 105 the valve P will be lifted when the train-line pressure rises to a value exceeding that of the somewhat depleted auxiliary reservoir, and the reservoir will be replenished by the 110 passage of the air along the route I have described including the feed groove p^2 , and 115 120 125 130

when replenished, its pressure will equal that of the train-line and close the valve P.

In the present case I purpose to make claims covering the particular form and arrangement of the valves P P' whereby an emergency application of the brake serves to shut off the auxiliary reservoir and admit the train-line pressure to the brake cylinders, while at the same time the communication with the auxiliary reservoir (which in one direction is limited by the small capacity of the feed groove) is, in the other direction, unrestricted and is directed, moreover, so as to act in immediate opposition to train-line pressure for closing the valve P at the point where it is necessary that the auxiliary reservoir be called upon to continue the supply to the brake after the first rush of air to the brakes from the train line has subsided, and the train-line pressure on valve P is reduced below the auxiliary reservoir pressure thereon.

The next feature of my invention relates to a device for equalizing the time required for brake-release on widely separated cars of a long train. It is a well known feature of the Westinghouse system that, in restoring the train-line pressure to release the brakes, the effect is retarded on the more remote cars by the necessity of not only filling the train-line with air, but also supplying from the train line the depleted auxiliary reservoirs. The train-line air must first fill the auxiliary reservoirs at the forward end of the train before its pressure can rise at the rear end. This requires considerable time, and until the reservoirs are thus re-filled, to compensate for the air drawn from them in the previous application of the brake, the train-line pressure cannot be fully restored and the brakes thereby released. The forward brakes are in consequence released before the rear ones, with danger under some circumstances of the train pulling apart and with danger of shock to the cars and the freight therein. To obviate this tendency, I provide each of my exhaust valves with what I may call a detainer, which serves to throttle more or less the outflow of air through the valve in the event of the valve being lifted suddenly beyond a certain point. By this device the exhaust valve will be throttled in proportion to the rapidity of pressure-rise in adjacent portion of the train pipe, as compared with the rapidity of pressure-drop in the brake cylinders. In other words this throttling action in my device is not produced merely by the increase of train-line pressure alone, nor is it affected in any way by the pressure in the auxiliary reservoir. No matter how suddenly or to what degree the exhaust valve may be opened, no throttling would occur if the brake pressure dropped with equal suddenness and to an equal degree, since the equi-

librium would follow synchronously with the change in train-line pressure. The decrease of the brake-cylinder pressure cannot, however, follow in exact synchronism with the increase in train-line pressure but lags behind it more or less, and it is this lag or differential between the rate of train-line increase and brake-cylinder decrease which gives the throttling action upon which I rely. Moreover, the throttling itself serves to increase the lag. Of course the throttling ceases in proportion to and as soon as the dropping brake pressure compensates for and corresponds to the rise in train-line pressure. Moreover, the more sudden and extreme the rise in train-line pressure the greater will be the throttling effect, and if the rise in train-line pressure is made slowly so that the brake exhaust follows it very closely, as would be the case at the rear cars of the train, no throttling action is produced.

In a long train the sudden application of the maximum air pressure to the train line naturally takes effect first and immediately at the forward end of the train and proceeds along the train in a sort of wave fashion, there being a difference in wave-phase at the different cars, and my device produces a corresponding difference in the rate of brake release so that the brakes on the first and last cars of the train are automatically reduced to any given point—say twenty pounds—at the same instant. The means by which I accomplish this are extremely simple, consisting merely of an enlargement or detainer S on the lower end of the exhaust valve k^2 below the seat thereof, which serves, when the valve seat is depressed, to partly re-close and restrict the outflow of air from the brake cylinder into the atmosphere. The form and size of the detainer S will determine the degree and time of its restricting effect. Taking any individual valve it will be apparent that a sudden increase of train-line pressure will cause the compression of the spring G and a corresponding depression of the seat of the valve k^2 , which will first open the valve as it departs from its seat and then reclose it as the seat approaches the detainer S. If, however, the sudden compression of the spring by the increase of train-line pressure were instantly released by a corresponding decrease of the brake pressure, the valve would be re-closed by the restoration of the normal equilibrium, but to the extent that the drop in brake-cylinder pressure lags behind, both by the throttling effect and by the natural time requirement by the outflow of the air, to the same extent will the restoration of equilibrium be retarded. Of course if the rise in train-line pressure were so gradual that the outflow of air from the brake cylinders would keep pace with it there would be merely the normal opening.

of the valve k^2 without any throttling of it by a super-normal movement of the valve seat, and this is the action which takes place at the rear cars of the train. The valve seat thus intervenes between the seating surface on the under side of valve k^2 and what might be called a second seating surface on the upper side of detainer S, although there is no actual seating on the detainer S, but only an approximation thereto sufficient to give the throttling aforesaid.

What I claim as new and desire to secure by Letters Patent is:

1. The combination in a triple valve, of 15 inlet and exhaust valves for the brake cylinder controlled by a balance of train-line and brake-cylinder pressures against a standard pressure, means for admitting either auxiliary-reservoir air or train-line 20 air to the brake cylinder according to the rate of train-line decrease, and means for shutting off the train-line air and admitting the auxiliary-reservoir air by the differential effect of the auxiliary-reservoir and train-line pressures.

2. The combination in a triple valve, of 30 inlet and exhaust valves for the brake cylinder controlled by a balance of train-line and brake-cylinder pressures against a standard pressure, means for shutting off the auxiliary reservoir from the brake cylinder and connecting the train line thereto according to the rate of train-line pressure variation, and means for subsequently cutting off the train-line air and admitting the auxiliary-reservoir air to the brake cylinder dependent upon the balance of auxiliary-reservoir pressure against the train-line pressure.

3. The combination in a triple valve, of 40 inlet and exhaust valves for the brake cylinder controlled by a balance of train-line and brake-cylinder pressures against a standard pressure, a chamber communicating with the brake cylinder through the inlet valve aforesaid, a valve between said chamber and the auxiliary reservoir, means for closing the last named valve when the pressure in said chamber falls below the train-line pressure, and means for subsequently opening it when the pressure in said chamber falls below the pressure in the auxiliary reservoir.

4. The combination in a triple valve, of 50 inlet and exhaust valves for the brake cylinder controlled by a balance of train-line and brake-cylinder pressures against a standard pressure, a chamber communicating with the brake cylinder through the said inlet valve, a valve for connecting said chamber alternately with the auxiliary reservoir and the train line, and a check-valve between said chamber and the auxiliary reservoir restricting the flow into, while permitting a free flow out of, the auxiliary reservoir.

5. The combination in a triple valve, of

inlet and exhaust valves for the brake cylinder controlled by a balance of train-line and brake-cylinder pressures against a standard pressure, a chamber communicating with the brake cylinder through the said inlet valve, a check-valve between said chamber and the train line, and a second check-valve between the said chamber and the auxiliary reservoir.

6. The combination in a triple valve, of 70 inlet and exhaust valves for the brake cylinder controlled by balance of train-line and brake-cylinder pressures against a standard pressure, a chamber communicating with the brake cylinder through the said inlet valve, 75 a check-valve between said chamber and the train line, a second check-valve between the said chamber and the auxiliary reservoir, and a connection between said chamber and the auxiliary reservoir controlled by the first 80 named check-valve.

7. The combination in a triple valve, of 85 inlet and exhaust valves for the brake cylinder controlled by a balance of train-line and brake-cylinder pressures against a standard pressure, a chamber communicating with said brake cylinder through the said inlet valve, a check-valve between said chamber and the train line, a passageway leading from the said chamber to the auxiliary reservoir and controlled by the said 90 check-valve, and a second check-valve located in the said passageway.

8. The combination in a triple valve of 100 inlet and exhaust valves for the brake cylinder controlled by a balance of train-line and brake-cylinder pressures against a standard pressure, a chamber communicating with the brake cylinder through the said inlet valve, a check-valve between the said chamber and the train line, and a second check-valve between said chamber and the auxiliary reservoir provided with a by-pass feed groove.

9. The combination in a triple valve, of 110 inlet and exhaust valves for the brake cylinder controlled by a balance of train-line and brake-cylinder pressures against a standard pressure, and a connection between the train line and the auxiliary reservoir 115 controlled by two check-valves one provided with a by-pass feed groove.

10. The combination in a triple valve, of 120 inlet and exhaust valves for the brake cylinder controlled by a balance of train-line and brake-cylinder pressures against a standard pressure, a chamber communicating with the brake cylinder through said inlet valve, a check valve between said chamber and the train line, a cut off between said train line and the auxiliary reservoir, and a check-valve between said cut off and the auxiliary reservoir.

11. The combination in a triple valve, of 130 inlet and exhaust valves for the brake cylin-

der controlled by a balance of train-line and brake-cylinder pressures against a standard pressure, a chamber communicating with said brake cylinder through the said inlet valve, a check-valve between said chamber and the train line, and a passageway from the auxiliary reservoir to the said chamber directed against the said check-valve whereby the inflow from the auxiliary reservoir to

10 the chamber tends to close the said check-valve.

12. In a triple valve for air brakes, the combination with the exhaust valve of the brake cylinder, and means for throttling said valve dependent on the ratio between the rate of pressure increase in the train line and the rate of pressure decrease in the brake cylinder.

13. In a triple valve for air brakes the combination with the exhaust valve of the brake cylinder, of means for operating said valve by the resultant of the train-line and brake-cylinder pressures acting in opposition to a standard pressure, and means for throttling said valve dependent on the ratio between the rate of pressure increase in the train line and the rate of pressure decrease in the brake cylinder.

14. In a triple valve for air brakes, the combination with the exhaust valve of the brake cylinder, of operating devices therefor controlled by the resultant of the train-line and brake-cylinder pressures acting in opposition to a standard pressure, and means

for controlling the opening of said exhaust valve according to the rate of increase in train-line pressure upon the application of the train-line pressure to release the brakes.

15. In a triple valve for air brakes, the combination with the exhaust valve of the brake cylinder of throttling devices therefor controlled by the rate of pressure increase in the train line with respect to the rate of pressure decrease in the brake cylinder.

16. In a triple valve for air brakes, the combination with the exhaust valve of the brake cylinder, of a graduated release device therefor and a throttling device controlled by a super-normal opening movement of the valve.

17. In a triple valve for air brakes, the combination with the exhaust valve of the brake cylinder having double surfaces, of a valve seat between said surfaces controlled by the resultant of train line and brake cylinder pressures acting in opposition to standard pressure.

18. In a triple valve for air brakes the combination with the exhaust valve k^2 and its seat, of the detainer S and a valve seat intervening between said valve and detainer.

In witness whereof I have hereunto set my hand before two subscribing witnesses this 28th day of February, 1907.
